UNITED STATES PATENT OFFICE

LEWIS R. HEIM, OF DANBURY, CONNECTICUT, ASSIGNOR, BY MESNE ASSIGNMENTS, TO CINCINNATI GRINDERS INCORPORATED, OF CINCINNATI, OHIO, A CORPORATION OF OHIO

GRINDING

Application filed October 20, 1923, Serial No. 669,693. Renewed March 12, 1929.

This invention relates to grinding and more particularly to an art and apparatus for grinding articles or bodies having a round or circular cross section.

5 One of the objects of this invention is to provide apparatus for grinding bodies of round section that will be capable of a high speed of production, and that may be readily adapted to meet the varying requirements and 10 conditions of practical use. Another object is to provide apparatus of the above nature that will be of rugged and durable construction throughout and of dependable and efficient action. Another object is to 15 provide apparatus of the above character for effectively and efficiently controlling the relation of the work to be operated upon with respect to the operative wheels and for insuring the proper and desired action of the 20 wheels on the work piece. Another object is to provide a simple and practical art of grinding articles of round section which may be readily and conveniently carried on and with a high degree of accuracy and uniformity in 25 result. Other objects will be in part obvious or in part pointed out hereinafter.

The invention accordingly consists in the features of construction, combinations of elements, arrangements of parts and in the several steps and relation and order of each of the same to one or more of the others all as will be illustratively described herein, and the scope of the application of which will be indicated in the following claims.

35 In the accompanying drawings, in which is shown one of various possible embodiments of the mechanical features of this invention,

Figure 1 is a rear view of the apparatus in assembled relation;

40 Figure 2 is a sectional view on an enlarged scale taken substantially along the line 2—2 of Fig. 1;

45 Figure 3 is a fragmentary sectional view as seen on the line 3—3 of Fig. 1, showing certain portions of the operative mechanism, and

Figure 4 is a sectional view on the line 4—4 of Fig. 3;

50 Figure 5 is a fragmentary end elevation

of a portion of the apparatus as seen along the line 5—5 of Fig. 1; and

Figure 6 is a fragmentary, diagrammatic plan view, showing the relation of the two wheels, one to the other, of the apparatus.

Similar reference characters refer to similar parts throughout the several views of the drawings.

Referring now to the drawings and more particularly to Fig. 1, there is shown at 10 a main supporting frame of any suitable construction and height, the frame 10 being provided upon the upper part thereof with suitable longitudinally extending and transversely spaced ways 13 adapted to guide for 15 sliding movement therein the carriages 11 and 12, one adjacent each end of the main frame 10. At the adjacent ends of the carriages 11 and 12 are provided pairs of transversely spaced bearings 15 and 16, respectively, in which are rotatably supported the 20 shafts 17 and 18, respectively. In Fig. 2 this construction is clearly illustrated with respect to the carriage 11, and it will be understood that the bearings 16 of the carriage 12 25 are in general of substantially similar construction and arrangement as are the bearings 15 of the carriage 11.

Referring still to Fig. 2, it will be noted that the shaft 17 overhangs the right-hand 30 or front side of the carriage 11, that is, the side remote from the observer viewing Fig. 1, and upon this overhanging end of the shaft 17 is supported to rotate with the shaft 17 a grinding wheel 22 made of any suitable 35 abrasive material. The grinding wheel 22 is adapted to be rotated at a suitable grinding speed by means of a belt 21 (see Fig. 2) which coacts with an elongated pulley 19 mounted on the shaft 17 and intermediate of the 40 spaced bearings 15. The belt 21 makes connection with any suitable source of power, and preferably to a pulley or other source of power underneath the carriage 11 and within the main frame 10.

The shaft 18 supported in the spaced bearings 16 of the carriage 12 similarly overhangs the front side of the carriage 12 and at its thus-overhanging end supports what will hereinafter be termed a regulating 45

wheel 24 (see Fig. 1) conveniently and preferably made of a suitable abrasive material, and by the arrangement hereinabove described it will be noted that the two wheels 22 and 24 are thus supported adjacent one another. This relation is shown diagrammatically in the diagrammatic view of Fig. 6. The regulating wheel 24 is driven by means of a pulley 25 (see Fig. 1) mounted intermediate of the spaced bearings 16 of the carriage 12 and adapted to be driven by a belt 26 running over the pulley 25. The belt 20 is connected to any suitable source of power, preferably to a pulley or other source housed within the main frame 10.

At this point it may be pointed out that the grinding wheel 22 and the regulating wheel 24 are rotated by means of their respective pulleys at speeds which are respectively high and low and in the directions indicated by the arrows in Fig. 1 and Fig. 6. The grinding wheel is thus made to present an operative surface traveling downwardly at high speed with respect to a work carrier 28 interposed between the two wheels and to be more clearly hereinafter described, and the regulating wheel 24 is thus made to present an operative surface which travels upwardly at a low speed with respect to the carrier 28. Preferably the regulating wheel 24, here shown as having a peripheral operative surface, is so related with respect to the work-supporting surface of the carrier 28 that there exists between the path of travel of the operative surface of the regulating wheel 24 and the path of movement of the work along the carrier 28 an inclination which is effective to tend to urge the work along the carrier in the direction of the arrow 28^a of Fig. 2. This relative inclination is preferably obtained by inclining the axis of rotation of the regulating wheel 24 in the vertical plane, where the regulating wheel takes the form of a peripherally acted wheel, as here illustrated, and may conveniently be brought about by making the bearing 16 adjacent the regulating wheel 24 of higher elevation than the bearing 16 remote from the regulating wheel 24. In Fig. 2 of the drawings this relation of the regulating wheel 24 and its shaft 18 is shown in dotted lines. It may here be noted that a tilting of two or three degrees in this manner relative to the path of travel of the work on the carrier 28 is sufficient to bring about a substantial component of force or thrust on the part of the regulating wheel surface in the direction of the arrow 28^a with respect to the carrier 28. The regulating wheel 24, presenting an operative surface traveling with respect to the work carrier 28 in the direction hereinbefore noted, is driven at such a speed that its operative surface controls the rotation of the work on the carrier 28 and, by reason of the relative inclination hereinabove mentioned, the regulating wheel is ef-

fective to urge the work along the carrier 28 and in the direction of the arrow 28^a. This action will be more readily understood hereinafter.

The wheels 22 and 24 are substantially enclosed in a protective casing 29, since they are operated with some suitable cooling fluid, such as water. This casing 29 is secured in any suitable manner to the front part of the main frame 10 and is of sufficient lateral and longitudinal expanse to permit of the adjustment and movement of the wheels as will be more clearly hereinafter described. As will be clearly seen in Fig. 2, this protective casing 29 is formed to provide a bridge portion 29^a at a point substantially intermediate of the two wheels and below their adjacent operative surfaces. This bridge portion 29^a, moreover, provides a substantially horizontally extending supporting surface upon which rests a frame member 30 detachably held in place as by the downwardly extending plate 31 and the cap screws 31^a passing therethrough and into the bridge portion 29^a of the casing 29. The frame member 30 will be seen to extend between the two wheels and supports two vertically extending posts 30^a and 30^b, one on each side of the two wheels. These two spaced posts 30^a and 30^b support the work carrier 28 as by means of the bolts 30^c and 30^d, respectively, the posts 30^a and 30^b being slotted vertically, as is clearly shown in Fig. 2, to permit the making of a vertical adjustment of the carrier 28 with respect to the operative surfaces of the two wheels.

It will be noted that the carrier 28, in being thus supported adjacent its ends, may have its respective ends adjusted vertically independent of one another. The carrier 28 may thus be given any desired degree of inclination with respect to the horizontal which may be demanded by the conditions of operation, but under the conditions of use herein illustratively set forth in connection with the features of this invention the work carrier 28 is positioned or adjusted with respect to its supporting posts 30^a and 30^b so that its upper supporting surface will be substantially horizontal, that is, the path of travel of the downwardly moving surface of the grinding wheel 22 (see Fig. 2) makes an angle of substantially 90° with respect to the supporting surface of the carrier 28.

The work carrier 28 preferably takes the form of an elongated bar, the upper supporting surface of which, shown at 28^e in Fig. 1, is inclined toward the operative surface of the regulating wheel 24. The work of round section supported upon the surface 28^e of the carrier 28 is thus urged toward the regulating wheel surface, thus insuring the maintenance of the work in contact with the regulating wheel surface when, as hereinafter more clearly described, the work carrier 28 is moved or displaced upwardly, as viewed in

both Figs. 1 and 2, for the purpose of disengaging the work from the operative surfaces of the two wheels. It may also at this point be noted that, as shown in Fig. 1, the adjacent operative surfaces of the two wheels, indicated at 22^c and 24^c, respectively, gradually approach one another and that this relation between the operative surfaces is most conveniently attained by making both wheels of the peripherally active type.

Where the work operated upon by the apparatus is not of uniform diameter throughout, as for example when it takes the form of headed stock such as a bolt 32 (see Fig. 2), the work can not be fed continuously along the carrier 28 by the action of the regulating wheel 24, as is the case where the work takes the form of rolls for roller bearings, for example. Accordingly, the carrier 28 is recessed at its forward end, as at 28^y, and is provided with a stop member adjacent its left-hand end to prevent the entry of the enlarged portion or head of the work between the two wheels. Thus in Fig. 2 is shown a stop member 28^b secured to the end of a rod 28^e slidably mounted in the bosses 28^d and 28^f of an auxiliary frame member 28^g detachably secured to the carrier 28 as by means of the clamping screws 28^h. A spring 28ⁱ is interposed between the left-hand end of the rod 28^e and the boss 28^f and tends to urge the rod 28^e to the left, as viewed in Fig. 2. The stop member 28^b may be adjustably positioned lengthwise of the carrier 28 to accommodate the apparatus for different lengths of work of the character, for example, of the bolt 32, by means of an upwardly extended arm 28^k adjustably mounted upon the rod 28^e as by the set screw 28^m so as to limit the movement of the rod 28^e to the left under the influence of the spring 28ⁱ. The work 32, assuming it to be positioned as shown in Fig. 2, in operative relation with respect to the two wheels, is thus not only positively rotated on the carrier 28 during the grinding action thereon of the grinding wheel 22, but also is positively held against the limiting stop 28^b by the action of the regulating wheel 24 in tending to urge the work 32 along the carrier in the direction of the arrow 28^a, where this action is desired to be employed.

As hereinabove noted, the stop member 28 and associated mechanism is mounted upon the auxiliary frame member 28^g so that these several parts may be removed from the carrier 28 to adapt the apparatus for work of substantially uniform diameter which, as above noted, may be continuously fed along the carrier and through the apparatus. It will be noted from Fig. 2, and also from Fig. 6, that the regulating wheel 24 has a broad operative surface active adjacent the carrier 28 thus permitting the regulating wheel to present a controlling surface of sufficient extent lengthwise of the carrier 28

to effectively "back up" either a plurality of cylindrical articles arranged successively upon the carrier 28, or headed stock or work, such as the bolt 32, of varying lengths, the latter being placed upon the carrier with the stop 28^b in position. The grinding wheel, however, has an operative surface the width of which in the direction of the length of the carrier 28 is less than the width of the surface of the regulating wheel, as is clearly shown in Fig. 6. The grinding wheel 22 is therefore, and in accordance with one of the features of this invention, moved lengthwise of the carrier 28 and preferably is reciprocated with respect to the work supported thereon. It will be understood that the grinding wheel 22, traveling at a grinding speed and performing the active cutting action upon the work, is therefore subjected to the maximum wear as between the two wheels. The wear on the grinding wheel, however, is not uniform since its greatest wear takes place at that portion of its operative surface adjacent that end of the carrier from which the work enters the grip of the wheels. The wheel must therefore be frequently trued in order that accuracy and uniformity in output be maintained. One of the dominant aims of this invention is to provide a grinding apparatus in which the frequency of truing of the wheels will be reduced and in which accuracy and constant uniformity of action may be maintained. The grinding wheel 22 is therefore made to change continuously its relation to the work operated upon so that more uniform wear and action may be achieved.

Referring now to Fig. 2, it will be seen that the shaft 17 of the grinding wheel 22 overhangs the carriage 11 at the rear side of the apparatus and it may be noted that this shaft and the bearings 15 in which it is rotatably supported are so arranged that the shaft 17 with the wheel 22 may be given a movement in an axial direction with respect to the fixed bearings 15 on the carriage 11. Thus it will be noted that the driving pulley 19 on the shaft 17 is a broad-faced pulley so that as the shaft 17 is moved to the right as viewed in Fig. 2 the driving connection through the belt 21 may be maintained throughout a material range of movement. The grinding wheel 22 may thus conveniently be given a movement lengthwise of the carrier 28. Preferably this movement is a reciprocatory movement and, where the work operated upon is cylindrical, and the work carrier 28 therefore arranged horizontally (or without inclination with respect to the path of travel of the surface of the grinding wheel) this movement of the grinding wheel 22 takes place in a direction substantially coincident with the tangent line of contact of the work on the carrier 28 with the grinding wheel 22. Thus, before describing in detail the mecha-

nism for bringing about the movement of the grinding wheel, it may be noted that the grinding wheel 22 is reciprocated or moved lengthwise of the carrier 28 as the regulating wheel 24 rotates and feeds the work on the carrier, where the work takes the form of cylindrical articles such as rolls for roller bearings, or as the work is rotated and held against the stop 28^b by the regulating wheel 24 where the work takes the form of headed stock, such as the bolt 32 of Fig. 2. As the grinding wheel 22 is reciprocated, it will be seen that first one end of its operative surface and then the other end begins the grinding or cutting action, and thus uniformity of wear throughout the extent of the operative surface of the wheel is maintained.

The grinding wheel 22 advantageously takes the form of a cylindrical wheel having, thus, a peripheral operative surface, since its reciprocating movement relative to the work on the carrier may be more simply effected by bringing about a movement of the shaft 17 of the wheel 22 relative to the supporting bearings 15 thereof.

Considering now the mechanism for conveying to the grinding wheel 22 this movement, and referring more particularly to Fig. 1, it will be seen that upon the one end of the shaft 18 upon which the regulating wheel 24 is supported there is mounted a helical gear 33, which meshes with a helical gear 34 mounted upon a shaft 35 extending transversely of the regulating wheel shaft 18 and 35 rotatably supported upon the rear side of the carriage 12. Thus the carriage 12 has mounted upon its rear side the spaced brackets 36 and 37 suitably formed to provide the bearings 38 and 39 respectively for rotatably supporting the shaft 35. At the left hand end of shaft 35, as viewed in Fig. 1, and preferably to the left of the helical gear 34, is mounted a gear 40 adapted to mesh with and drive a gear 41 rigidly mounted upon a shaft 42 rotatably supported in the bearing 43 conveniently formed in the bracket 36. The gears 40 and 41 may be proportioned one to another so as to obtain any desired speed ratio of the shaft 42 to the shaft 35, and as 45 illustratively shown in Fig. 1 the gears 40 and 41 bear such a relation to one another that the shaft 42 is driven at twice the speed of the shaft 35. In order to insure adequate support for the shaft 42, the left hand end 50 thereof is supported in a bifurcated bearing 44 formed in a bracket 45 and conveniently secured to the rear side of the main frame 10.

At the right hand end of the shaft 42, the latter carries a crank disk 46 (see Figs. 1, 3 and 5) which is formed to provide a T-slot 47 extending centrally and transversely thereof. The T-slot 47 accommodates the head 48^a of a bolt 48, the outer or right hand end of which, as seen in Fig. 1, supports rotatably a roller 49. By this construction, as

reference to Fig. 5 will clearly show, the roller 49, forming in effect a crank-pin, may be adjustably positioned along the T-slot 47, to vary at will the distance of the roller 49 from the center of the crank disk 46 and hence to vary at will the throw of the crank-pin 49.

The bracket 36 is formed to provide also two aligned and spaced bearings 50 and 51 in which is supported for oscillation therein a shaft 52 extending longitudinally of the main frame 10 at the rear thereof and toward the grinding wheel end of the apparatus. The left hand end of the shaft 52, referring still to Figure 1, after passing through the spaced bearings 44^a of bracket 45, is supported in the spaced bearings 53 and 54 formed in the lower end of a bracket 55 secured in any convenient manner, as by bolts, to the rear side of the grinding wheel carriage 11 (see also Fig. 2). Between the spaced bearings 53 and 54 of the bracket 55 there is mounted upon the shaft 52 an upwardly extending arm 56, a key 57 locking the parts together so that whatever movement of the shaft 52 about its axis takes place is also conveyed to the arm 56. The key 57, however, coacts with a keyway 52^a extending lengthwise of the shaft 52, so that the operative relation above described between the shaft 52 and the arm 56 may be maintained irrespective of whatever relative movement may take place between these parts in the direction of the axis of the shaft 52.

Referring now to Figs 1 and 2, it will be noted that the rear end of the grinding wheel shaft 17 is reduced in section at its extreme end as at 17^a, and upon this reduced end 17^a is positioned a yoke 58 having a downwardly extended arm 58^a connected to the upper end of the arm 56 through the link 59. The yoke 58 is relatively loosely mounted upon the reduced portion 17^a of the shaft 17 so as to permit free rotation of the latter therein, but is held against axial movement relative to the shaft 17 by means of a collar 60 rigidly secured to the extreme end of the shaft. A thrust bearing 61 of any suitable construction is interposed between the yoke 58 and the collar 60 and another thrust bearing 62 is interposed between the yoke 58 and the main portion of the shaft 17. By this construction the shaft 17 may freely rotate with respect to the yoke 58 and it will be seen (see Fig. 1) that an oscillation of the shaft 52 will, through the arm 56 and the link 59, move the shaft 17 and hence the grinding wheel 22 in an axial direction, the thrust bearings 61 and 62 acting to eliminate friction between the parts as well as to avoid binding therebetween.

The shaft 52 is swung about its axis to move the grinding wheel lengthwise of the work support 28 by means of the crank-pin or roller 49 hereinbefore described. The mech-

130

anism with which the crank-pin 49 coacts is conveniently and preferably mounted between the spaced bearings 50 and 51 and at the right hand end of the shaft 52 (see Fig. 1). This mechanism comprises preferably a crank arm 63 (see Figs. 1, 3 and 4) sleeved at its lower end as at 63^a to permit locking of the arm 63 to the shaft 52 as by means of the pins 52^b for example and to provide also an outer bearing surface for the lower end 64^a of an upwardly extending arm 64, the upper and left hand face of which is provided with a longitudinally extending slot 64^b within which the roller or crank-pin 49 engages. Thus, as the shaft 42 rotates the crank disk 46, the member 64 is made to oscillate about the axis of the shaft 52, and if the member 64 is locked to the arm 63 (see Fig. 4), the oscillating movement of the member 64 is communicated to the shaft 52 and hence to the grinding wheel 22 through the arm 63. Thus in Fig. 4 is shown a clamping screw 65 for locking these members together.

Assuming that the member 64 is locked to the arm 63, the grinding wheel 22 will be reciprocated lengthwise of the carrier 28 throughout a stroke, the extent of which may be adjusted by adjustably positioning the follower or crank-pin 49 with respect to the crank disk 46. The regulating wheel 24, rotating at a materially slower speed than the grinding wheel 22, which latter wheel must be rotated at a sufficient speed to produce grinding action, thus forms a convenient and relatively low speed source of power for producing the traversing movement of the grinding wheel with respect to the operative surface of the regulating wheel 24. As the grinding wheel 22 is thus reciprocated, it will be noted that its motion throughout a given stroke is substantially simple harmonic in nature. This is advantageous inasmuch as the grinding wheel is thus given a greater speed of movement throughout substantially the middle part of its stroke and a lesser speed of travel at the ends of the stroke. Substantial uniformity of grinding action is thus assured, since the lesser portion of the grinding wheel effective on the work at the ends of the stroke is given more time to act upon the work.

Under certain conditions of operation, it may be desirable to bring the grinding wheel to a pause or to a position of momentary rest at the ends of its stroke, in order to compensate for the impossibility of reciprocating or moving the grinding wheel completely past the end of the work operated upon. This is particularly true where the work takes the form of headed stock, assumed hereinabove by way of example as the bolt 32 (see Fig. 2). In order therefore to permit the above-mentioned action to take place, the clamping screw 65, (which as seen in Fig. 4 is threaded into the member 64) passes through an arcu-

ate slot 63^b in the arm 63 (see Fig. 3). Hence, if the screw 65 is loosened sufficiently to unclamp the members 63 and 64, the resultant lost motion connection between the members 63 and 64 is effective to bring about a pause at the end of each oscillating movement of the arm 63 with the shaft 52. The arm 56 (see Fig. 2) moving in unison with the shaft 52, will likewise be halted at the end of each oscillation with a resultant like action at the end of each stroke of the grinding wheel 22. The shortening of the stroke of the grinding wheel 22 resulting from the lost motion connection between the members 63 and 64 may be compensated for, if necessary, or brought back to the desired extent by adjusting the crank-pin 49 relative to the crank disk 46 (see Figure 3).

In order that the length of the pause at the end of the stroke of the grinding wheel may be adjusted, the length of the slot 63^b is made adjustable by means of the two oppositely mounted adjusting screws 63^c and 63^d threaded into the opposite ends of the arm 63 and having their end portions extending into the respective ends of the slot 63^b. Thus the amount of lost motion between the members 63 and 64, and hence the length of the interval of rest of the grinding wheel 22, may be adjusted at will.

It is to be noted that not only is the length of the stroke of the grinding wheel 22 lengthwise of the carrier 28 made adjustable so that it may be made commensurate with the length of the work, such as the bolt 32, operated upon, but also the position of the range of movement of the grinding wheel 22 may be exactly predetermined. Thus, the parts 63 and 64 (see Figs. 4 and 3) may be clamped together in any desired relation of angular displacement therebetween, the locus of operation of the grinding wheel 22 being thus, for a given stroke, fixedly and exactly predetermined relative to the carrier or the work thereon. This same predeterminedation of the locus of operation of the grinding wheel 22 may be made also where the lost motion connection between the arm 63 and the crank operated member 64 is utilized, since it will be seen that, by reason of the adjusting screws 63^c and 63^d, the effective slot 63^b may in effect be not only lengthened or shortened, but also displaced with respect to the arm 63. It will thus be seen that the movement of the grinding wheel 22 may be accurately and precisely predetermined to meet the particular character or nature of the work operated upon.

It will thus be seen that the grinding wheel 22 will be subjected to a more uniform wear, thus insuring the maintenance of continued accuracy and uniformity in grinding. It may also be pointed out that in addition to the normal accuracy of action of the grinding wheel upon the work, the grinding operation is insured of a relatively fixed degree of ac-

curacy because of the movement of the grinding wheel lengthwise of the carrier.

Referring now to Fig. 2, it will be seen that the frame member 30 is bored out as at 5 30° throughout substantially its entire extent. This bore 30° is preferably cylindrical throughout in order that there may be housed within the member 30 for longitudinal movement with respect thereto a substantially cylindrical bar 68 having at two spaced points therein and at the upper surface thereof the inclined surfaces 68^a and 68^b, suitably formed in the bar 68 as by cutting away a corresponding portion thereof. The inclined surfaces 68^a and 68^b are adapted to coact with the downwardly extending studs 30^f and 30^g preferably integrally formed with the supporting posts 30ⁱ and 30^j, respectively, and upon which posts the carrier 28 is mounted. 10 The frame member or casing 30 is suitably extended upwardly, as at 30^h and 30^k, these upwardly extended portions 30^h and 30^k having formed therein suitable vertically extending openings or passages for permitting 15 the studs 30^f and 30^g to pass into the casing member 30 for coaction with the inclined surfaces 68^a and 68^b, respectively. Suitable springs 69 and 70 connect the carrier 28 to the frame member 30 in order that the studs 20 30^f and 30^g may be effectively maintained in operative contact with the inclined surfaces 68^a and 68^b, respectively.

The rear or left hand end of the bar 68, referring still to Fig. 2, is pivotally and detachably connected through the pin 68^e to a rod 68^d extending rearwardly of the apparatus or to the left as viewed in Fig. 2. The left hand end of the rod 68^d is pivotally connected, as at 71, to the upper end of a cam yoke 40 72, the lower end of which is pivoted upon the shaft 52 and held against displacement lengthwise of the machine in that it is interposed between the two parts of the bifurcated bearings 44^a in the bracket 45 (see Fig. 1).

The cam yoke 72, as will be seen in Fig. 2, provides in effect two arms 72^a and 72^b extending substantially vertically and spaced from one another in a lateral direction in order to receive therebetween a cam 73, the hub 50 73^a of which is splined, as at 42^a, to the shaft 42 (see also Fig. 1). The hub 73^a of the cam 73 is interposed between the spaced portions of the bifurcated bearing 44 of the bracket 45 (see Fig. 1) in order to hold the cam from 55 relative displacement with respect to the cam yoke 72. It will be noted, however, that relative movement between the shaft 42 and the cam 73 in an axial direction may freely take place without disturbing the operative connection of the cam 73 with the shaft 42.

The cam 73 is provided with a cam surface 73^b adapted to coact alternately with the arms 72^a and 72^b of the cam yoke 72, causing the yoke 72 to be swung about the shaft 52 first 60 in a counter-clockwise direction and, after an

interval of time, in a clockwise direction, it being understood that the shaft 42 rotates preferably continuously and in clockwise direction as viewed in Fig. 2. In Fig. 2 of the drawings the cam surface 73 is shown in position about to coact with the arm 72^b of the yoke 72. As the cam 73 is rotated from this position, the yoke 72 is swung in a counter-clockwise direction, thus moving the rod 68^d and the bar 68 to the left. When this occurs, 70 the inclined surfaces 68^a and 68^b of the bar 68 are effective to raise the carrier supporting posts 30ⁱ and 30^j through their respective studs 30^f and 30^g, thus moving the carrier 28 upwardly, as viewed in both Figs. 2 75 and 1, and hence positioning the work 32 between portions of the approaching operative surfaces 22^c and 24^e of the grinding wheel 22 and the regulating wheel 24, respectively, which are more distant from one 80 another. The work is thus carried upwardly and out of active operative relation with respect to both wheels.

During this action, it may be pointed out 85 that the inclined supporting surface 28^e of the carrier 28 is effective to urge the work 32 toward the regulating wheel 24, thus effectively holding it out of contact with the grinding wheel 22 and thus preventing undesired grinding action thereon. The work 32 may 90 thereupon be removed from the carrier.

As the rod 68^d is moved to the left, it will 95 be noted that it carries with it in like direction a disk member 74 adjustably positioned upon the rod 68^d, as by the set screw 74^a. 100 This disk member 74 is adapted to coact with the lower end 78^a of a lever 78 extending in a general upward direction and pivoted to the carrier 28 as at 78^b. The upper end 78^c of the lever 78 carries a pin or stud 78^d engaged in 105 the upper bifurcated end 28^e of the rod 28^k, which, as hereinbefore noted, is secured at its lower end to the plunger rod 28^e.

As the disk 74 is thus moved to the left, 110 it swings the lever 78 in clockwise direction about its pivot 78^b, thus moving the vertically extending arm 28^k and the plunger rod 28^e to the right. The stop member 28^b, against which the work 32 abuts, as hereinbefore described, is thus carried to the right 115 and moves the work 32 lengthwise of the carrier 28 and out of the apparatus. As this action takes place, it will be noted that the inclined surface 28^e of the carrier 28 holds the work 32 in engagement with the slow 120 moving regulating wheel 24 and out of contact with the grinding wheel 22, thus preventing accidental or undesired grinding contact between the grinding wheel 22 and the work 32.

As is clearly shown in Figure 2, the disk 125 74 is so positioned on the rod 68^d that an appreciable movement thereof may take place before the ejecting movement of the plunger 28^e begins. Thus the upward movement of 130

the carrier 28 to remove the work from the grip of the wheels is well initiated before the ejecting of the work takes place. As above noted, the member 74 may be adjustably positioned lengthwise of the rod 68^a, the set screw 74^a permitting the disk member 74 to be locked in adjusted position; by adjusting the position of the disk 74 lengthwise of the rod 68^a, the extent of movement (in a direction toward the left, as viewed in Figure 2) of the disk 74 before it contacts with the lower end 78^a of the lever 78, may be adjusted or predetermined at will, and it will further be noted that thereby the extent of the lost motion that takes place in the thus effected connection between the rod 68^a and the ejecting mechanism 28^e may be predetermined at will.

While the work carrier 28 is momentarily held in its uppermost position and after the ejection of the work 32 has taken place, a new work piece may be positioned upon the carrier, so that when the downward movement of the carrier 28 takes place, due to the movement of the operating bar 68 to the right by the cam 73, the new work piece to be operated upon may be presented to the wheels for action thereon. During the downward movement of the carrier 28, the spring 28ⁱ is free to permit it to retract the plunger rod 28^e and to position the stop member 28^b in the position previously predetermined by the arm 28^k on the rod 28^e. It will be noted that as the carrier 28 is thus moved downwardly, the inclined surface 28ⁱ thereof maintains the new work piece 32 in contact with the regulating wheel 24, thus avoiding accidental or premature grinding action on the work by the grinding wheel 22, and also permitting the regulating wheel to start the uniform rotation of the work 32 preliminarily to the presentation of the work 32 to the grinding wheel 22. Also the regulating wheel is thus free to urge and hold the work piece 32 against the stop 28^b, it being noted that the retraction of the stop member 28^b in response to the spring 28ⁱ takes place before the return to its lowermost position of the carrier 28. A pair of adjustable stop members 30^x and 30^y threaded into the frame member 30 act to limit the downward movement of the carrier 28 to the desired or predetermined extent.

As hereinbefore noted, the cam 73 and the crank disk 46 are preferably mounted upon the same shaft 42, but they are so related to one another that, as the cam 73 begins to swing the yoke 72 to the left, referring still to Figure 2, thus to raise the work carrier 28, the crank disk 46, through its crank pin 49 and associated mechanism will have moved the grinding wheel 22 to the end of one of its strokes relative to the work carrier. Thus, the grinding wheel 22 is preferably brought to the end of its stroke in a direction from the right to the left as viewed in Figure 2 by the crank pin 49 and associated mechanism whereupon a continued clockwise rotation of the shaft 42 with its cam 73 will be effective to bring about the raising of the work carrier 28 and the discharge of the work therefrom as hereinbefore described. The cam 73 is effective to hold the carrier in its uppermost position for an interval of time sufficient, first to permit the positioning on the carrier 28 of a new work piece 32, and second, to permit the crank pin 49 and its associated mechanisms to give the grinding wheel 22 a retrograde movement to the right and into the dotted line position 22^c, clearly shown in Figure 2. Thereupon the continued rotation of the cam 73 brings it into coaction with the arm 72^b of the cam yoke 72 to move the carrier 28 downwardly to present the work piece 32 to the wheels. By reason of the relation of the cam 73 to the yoke 72, this return or downward movement of the carrier 28 takes place more slowly than does the upward movement of the carrier 28, as will be clear from a consideration of Figure 2. This is advantageous in that the work 32 is thus substantially gradually placed into operative relation to the two wheels.

The carrier 28 having thus been moved downwardly with the work thereon, is held in this position for such an interval of time until the cam member 73 comes into coaction with the arm 72^a of the cam yoke 72, whence the above described cycle is repeated. This interval of time, however, is sufficient to permit the crank disk 46 with its associated mechanisms to move the grinding wheel 22 lengthwise of the carrier and in a direction from the right to the left assuming finally the position shown in full lines in Figure 2.

As has been hereinbefore clearly described, the mechanism for moving the grinding wheel 22 may be readily arranged to permit a pause to take place at the end of each stroke of movement of the grinding wheel 22 along the carrier 28. The mechanism is preferably thus adjusted in order that the effective upward movement of the carrier 28 and its subsequent downward movement may take place during the respective pauses at the ends of the moving strokes of the grinding wheel 22.

During the movement of the grinding wheel 22 relative to the work carrier 28 when the latter is in its lowermost position, the regulating wheel 24 is effective to hold securely the work 32 against the stop 28^b, it being noted that the preferred movement of the wheel 22 during its grinding action is from the right to the left as viewed in Figure 2. If, however, it is desired to make the operative grinding stroke of the grinding wheel 22 take place in a direction from the left to the right, the crank pin 49 (see Figure 5) may be displaced 180° by moving it to the other

side of the center of the crank disk 46 and along the T-slot 47, thus reversing the strokes of the grinding wheel 22 with respect to the successive or alternate positions which the 5 work carrier 28 is made to assume as hereinbefore clearly described.

Referring now to Figure 1, it will be noted that, in order to permit adjustment of the 10 wheels 22 and 24 toward or away from one another, as may be necessary for adapting the apparatus for work of different diameters, a hand-wheel 66 operates a sleeve member 67 in threaded engagement with the carriage 11 and another hand-wheel 76, 15 operates a shaft 77 in threaded engagement with the carriage 12 and passing preferably through the sleeve 67. As hereinbefore described, the cam 73 is splined upon the shaft 42 and the arm 56 which moves the grinding 20 wheel 22 is splined upon the shaft 52. Thus either carriage may be freely adjusted along its respective ways without disturbing the operated connections between these several parts.

If it is desired to operate the apparatus 25 without reciprocating the grinding wheel 22 relative to the work on the work carrier 28, as may for example be desired when work of relatively short lengths is operated upon, the 30 clamping screw 65 (see Figures 1 and 4) may be removed, thus disconnecting the arm 63 from the arm 64. The arm 64 may then freely oscillate in response to the crank pin 49 without, however, transmitting its oscillating 35 movement to the arm 63, which, through the shaft 52 and the arm 56, controls the movement of the grinding wheel 22 as hereinbefore described.

Also, if it is desired to maintain the 40 carrier 28 in fixed position, with or without the reciprocation relative thereto of the grinding wheel 22, as may be desired when, for example, work of uniform diameter is continuously and successively fed through the apparatus, the operating rod 68^a (see Figure 45 2) may be disconnected with the cam yoke 72 by removing the detachable pin 71, permitting the yoke 72 to oscillate freely in response to the cam 73, but without transmitting its periodic movements to the operating 50 bar 68. At this point it may be noted that the ejecting mechanism may be readily detached from the carrier 28, in order to permit work of uniform diameter to be fed 55 continuously through the apparatus.

The forward end of the operating bar 68 is provided upon its under side with a rack 68^f with which meshes a gear 85 adapted 60 to be manually operated by means of the handle 86. Thus, in case it is desired to manually operate the bar 68, the pin 71 hereinabove mentioned may be taken out to disconnect the bar from the cam yoke 72, and thus to permit 65 the free manual control of the longitudinal

movements of the operating bar 68 to raise or lower the work carrier 28 as desired.

The upper end of the lever 78 has pivotally connected to it a rod 87 extending forwardly through and slidably supported in a bracket 70 88 secured to the protective casing 29, this rod 87 terminating in a handle member 89 to permit manual swinging of the lever 78 about its pivot 78^b. Thus, should it be desired to control manually the ejecting movements of 75 the plunger 28^c, the disk member 74 is moved along the rod 68^d to such a position that it is maintained, throughout its own movements, out of contacting relation with respect to the lever end 78^a of the lever 78. In this manner free manual control of the ejecting mechanism and the elimination of the automatic control thereof may be brought about.

Referring now again to Figure 1, it will be noted that upon the carriages 11 and 12 are mounted truing devices, generally indicated at 80 and 81 respectively. These devices may take the form, for example, of those shown in my co-pending application, Serial No. 619,373, filed February 16, 1923.

It will thus be seen that there has been provided in this invention an art and apparatus for grinding in which the several objects hereinabove set forth are achieved and many advantages attained. It may be pointed out 95 that the apparatus is of thoroughly practical construction and is of such flexibility that it may be readily and conveniently adapted to meet the varying conditions of practical use. Moreover, it will be seen that the above and 100 many other advantages are successfully attained with the achievement of a high degree of accuracy in result, in that the inherent accuracy of the two wheels in their action upon the work is effectively combined with the high 105 degree of accuracy resulting from the movement relative to the work itself of the grinding wheel.

I make herein no claim to the parts per se 110 that coact to hold the work axially immovable during the reciprocation of the grinding wheel, inasmuch as I have fully disclosed and claimed these features in my copending application Serial No. 669,899, filed October 22, 1923.

As many possible embodiments may be 115 made of the mechanical features of the above invention and as the art herein described might be varied in various parts all without departing from the scope of the invention, 120 it is to be understood that all matter herein set forth or shown in the accompanying drawings is to be interpreted as illustrative and not in a limiting sense.

I claim as my invention:

1. In apparatus of the character described, in combination, a grinding wheel adapted to be rotated at a relatively high speed, a regulating wheel adapted to be rotated at a relatively low speed, said wheels being adapted 130

to present adjacent operative surfaces traveling in opposite directions, a carrier extending between said wheels for supporting work of round section in operative relation to said oppositely traveling operative surfaces of said wheels, means for giving said grinding wheel a reciprocating movement relative to the work, and means adapted to permit a pause to take place at the end of a stroke in 10 said reciprocating movement of said grinding wheel.

2. In apparatus of the character described, in combination, a grinding wheel adapted to be rotated at a relatively high speed, a regulating wheel adapted to be rotated at a relatively low speed, said wheels being adapted to present adjacent operative surfaces traveling in opposite directions, a carrier extending between said wheels for supporting work 20 of round section in operative relation to said oppositely traveling operative surfaces of said wheels, automatic means for changing the relation of the grinding throat formed by said grinding wheel, regulating wheel 25 and work carrier with respect to the work, and means for giving said grinding wheel a reciprocating movement in a direction substantially coincident with the tangent line of contact of said wheel with the work, said 30 last-mentioned means including a rotatable crank pin, a member oscillated thereby, a member connected to said grinding wheel and adapted upon movement to move the grinding wheel, and means for adjustably connecting 35 together said two members whereby the reciprocations of said grinding wheel may be timed with respect to said automatic means.

3. In apparatus of the character described, in combination, a grinding wheel adapted to be rotated at a relatively high speed, a regulating wheel adapted to be rotated at a relatively low speed, said wheels being adapted to present adjacent operative surfaces traveling in opposite directions, a carrier extending between said wheels for supporting work of round section in operative relation to said oppositely traveling operative surfaces of said wheels, automatic means for changing the relation of the grinding throat formed by said grinding wheel, regulating wheel and work carrier with respect to the work, and means for reciprocating said grinding wheel 50 in the general direction in which said carrier extends, said last-mentioned means including a crank pin mounted to permit its eccentricity to be changed at will, thereby to predetermine the length of its stroke, a member adapted to be oscillated by said crank pin, a member connected to said grinding wheel and adapted upon movement to move the grinding wheel, and means for adjustably connecting together said two members 55 in order to permit the reciprocations of said

grinding wheel to be timed with respect to said automatic means.

4. In apparatus of the character described, in combination, a grinding wheel adapted to be rotated at a relatively high speed, a regulating wheel adapted to be rotated at a relatively low speed, said wheels being adapted to present adjacent operative surfaces traveling in opposite directions, a carrier extending between said wheels for supporting work of round section in operative relation to said oppositely traveling operative surfaces of said wheels, means for adjusting one of said wheels toward or away from the other, and means operated from said regulating 70 wheel for conveying to said grinding wheel a traversing movement relative to the operative portion of said regulating wheel.

5. In apparatus of the character described, in combination, a grinding wheel adapted to be rotated at a relatively high speed, a regulating wheel adapted to be rotated at a relatively low speed, said wheels being adapted to present adjacent operative surfaces traveling in opposite directions, a carrier extending between said wheels for supporting work of round section in operative relation to said oppositely traveling operative surfaces of said wheels, means for adjusting said grinding wheel toward or away 80 from said regulating wheel, mechanism including an oscillating shaft for producing a reciprocating movement, and connections between said grinding wheel and said mechanism including a sliding connection with 85 said oscillating shaft effective to reciprocate said grinding wheel irrespective of the adjustment of the latter relative to said regulating wheel and in the general direction of 90 said carrier.

6. In apparatus of the character described, in combination, a carrier for supporting thereon work of round section, a regulating wheel positioned on one side said carrier and adapted to be rotated at a relatively low 100 speed, thereby to control the rotation of said work on said carrier, means including a slow speed shaft for driving said regulating wheel, a grinding wheel having a peripheral operative surface positioned on the other side 110 of said carrier and having a driving shaft adapted to rotate said grinding wheel at a relatively high speed, bearing means for supporting said grinding wheel shaft, an oscillating shaft extending transversely of said 120 grinding wheel shaft, mechanism driven from said slow speed shaft for oscillating said transverse shaft, and connections between said oscillating shaft and said grinding wheel shaft for communicating to the latter the oscillating movements of the former, thereby to give said grinding wheel a traversing movement relative to the operative surface 125 of said regulating wheel.

7. In apparatus of the character described, 130

in combination, a grinding wheel adapted to be rotated at a relatively high speed, a regulating wheel adapted to be rotated at a relatively low speed, said wheels being adapted to present approaching operative surfaces traveling in opposite directions, a carrier extending between said wheels for supporting work of round section having a work supporting surface inclined toward the operative surface of said regulating wheel, means mounting said work carrier adapted to permit said carrier to be displaced in a direction to change the relation of said work thereon with respect to said approaching operative surfaces, and power-driven means for displacing said carrier.

8. In apparatus of the character described, in combination, a grinding wheel adapted to be rotated at a relatively high speed, a regulating wheel adapted to be rotated at a relatively low speed, said wheels being adapted to present approaching operative surfaces traveling in opposite directions, a carrier extending between said wheels for supporting work of round section, means permitting said carrier to be displaced in a direction to change the relation of said work thereon with respect to said approaching operative surfaces, a member having an inclined surface and adapted upon movement thereof to displace said carrier, and power-driven means for moving said member.

9. In apparatus of the character described, in combination, a grinding wheel adapted to be rotated at a relatively high speed, a regulating wheel adapted to be rotated at a relatively low speed, said wheels being adapted to present approaching operative surfaces traveling in opposite directions, a carrier extending between said wheels for supporting work of round section, means permitting said carrier to be displaced in a direction to change the relation of said work thereon with respect to said approaching operative surfaces, a member having an inclined surface and adapted upon movement thereof to displace said carrier, and automatic means for periodically moving said member.

10. In apparatus of the character described, in combination, a grinding wheel adapted to be rotated at a relatively high speed, a regulating wheel adapted to be rotated at a relatively low speed, said wheels being adapted to present approaching operative surfaces traveling in opposite directions, a carrier extending between said wheels for supporting work of round section and adapted to be moved between said approaching operative surfaces of said two wheels, and power-driven means adapted to move said carrier from a position between more distant portions of said operative surfaces to a position between less distant portions of said operative surfaces, to halt said car-

rier, and then to move it from the latter position to the former.

11. In apparatus of the character described, in combination, a grinding wheel adapted to be rotated at a relatively high speed, a regulating wheel adapted to be rotated at a relatively low speed, said wheels being adapted to present approaching operative surfaces traveling in opposite directions, a movable carrier extending between said wheels for supporting work of round section and adapted to be moved between said approaching operative surfaces of said two wheels, and power-driven means adapted in recurring sequence to move said carrier from a position between more distant portions of said operative surfaces to a position between less distant portions of said operative surfaces and from the latter position to the former but with a dwell at the completion of each movement.

12. In apparatus of the character described, in combination, a grinding wheel adapted to be rotated at a relatively high speed, a regulating wheel adapted to be rotated at a relatively low speed, said wheels being adapted to present approaching operative surfaces traveling in opposite directions, a movable carrier extending between said wheels for supporting work of round section and adapted to be moved between said approaching operative surfaces of said two wheels, means for moving said carrier from a position between more distant portions of said operative surfaces to a position between less distant portions of said operative surfaces or from the latter position to the former, and means for moving said grinding wheel in the general direction in which said carrier extends.

13. In apparatus of the character described, in combination, a grinding wheel adapted to be rotated at a relatively high speed, a regulating wheel adapted to be rotated at a relatively low speed, said wheels being adapted to present approaching operative surfaces traveling in opposite directions, a movable carrier extending between said wheels for supporting work of round section and adapted to be moved between said approaching operative surfaces of said two wheels, automatic means adapted to move said carrier from a position between more distant portions of said operative surfaces to a position between less distant portions of said operative surfaces and from the latter position to the former, and power-actuated means for reciprocating said grinding wheel in the general direction in which said carrier extends, said last-mentioned means acting in timed relation with respect to said carrier moving means.

14. In apparatus of the character described, in combination, a grinding wheel adapted to be rotated at a relatively high speed, a regu-

lating wheel adapted to be rotated at a relatively low speed, said wheels being adapted to present approaching operative surfaces traveling in opposite directions, a movable carrier extending between said wheels for supporting work of round section and adapted to be moved between said approaching operative surfaces of said two wheels, a stop for limiting the movement of the work in an axial direction along said carrier, and power-driven means adapted to move said carrier from a position between more distant portions of said operative surfaces to a position between less distant portions thereof and from the latter position to the former.

15. In apparatus of the character described, in combination, a carrier for supporting thereon work of round section, a regulating wheel positioned on one side of said carrier and adapted to control the rotation of the work on said carrier, a grinding wheel positioned on the other side of said carrier and movable in the general direction of said carrier, a power-driven reciprocating member, and means connecting said member to said grinding wheel, said means including a lost-motion connection.

16. In apparatus of the character described, in combination, a grinding wheel adapted to be rotated at a relatively high speed, a regulating wheel adapted to be rotated at a relatively low speed, said wheels being adapted to present approaching operative surfaces traveling in opposite directions, a movable carrier extending between said wheels for supporting work of round section and adapted to be displaced in a direction to change the relation of said work thereon with respect to said approaching operative surfaces, means for intermittently moving said carrier from a position between more distant portions of said operative surfaces to a position between less distant portions of said operative surfaces and from the latter position to the former, means for giving said grinding wheel an operative stroke in the general direction of said carrier when the latter is in the latter position and for giving said grinding wheel a retrograde stroke when the carrier is in the former position.

17. In apparatus of the character described, in combination, a grinding wheel adapted to be rotated at a relatively high speed, a regulating wheel adapted to be rotated at a relatively low speed, said wheels being adapted to present approaching operative surfaces traveling in opposite directions, a movable carrier extending between said wheels for supporting work of round section and adapted to be displaced in a direction to change the relation of said work thereon with respect to said approaching operative surfaces, means for intermittently moving said carrier from a position between more

distant portions of said operative surfaces to a position between less distant portions of said operative surfaces and from the latter position to the former, means for giving said grinding wheel an operative stroke in the general direction of said carrier when the latter is in the latter position and for giving said grinding wheel a retrograde stroke when the carrier is in the former position, and means for permitting a pause to take place at the end of a stroke of said grinding wheel.

18. In apparatus of the character described, in combination, a grinding wheel adapted to be rotated at a relatively high speed, a regulating wheel adapted to be rotated at a relatively low speed, said wheels being adapted to present approaching operative surfaces traveling in opposite directions, a movable carrier extending between said wheels for supporting work of round section and adapted to be displaced in a direction to change the relation of said work thereon with respect to said approaching operative surfaces, means for intermittently moving said carrier from a position between more distant portions of said operative surfaces to a position between less distant portions of said operative surfaces and from the latter position to the former, means for giving said grinding wheel an operative stroke in the general direction of said carrier when the latter is in the latter position and for giving said grinding wheel a retrograde stroke when the carrier is in the former position, said last mentioned means being effective to cause said retrograde stroke to take place at a higher speed of movement than the operative stroke of said grinding wheel.

19. In apparatus of the character described, in combination, a grinding wheel adapted to be rotated at a relatively high speed, a regulating wheel adapted to be rotated at a relatively low speed, said wheels being adapted to present approaching operative surfaces traveling in opposite directions, a movable carrier extending between said wheels for supporting work of round section and adapted to be displaced in a direction to change the relation of said work thereon with respect to said approaching operative surfaces, means for relatively adjusting one of said wheels and said carrier to vary the distance therebetween, and means operated from said last mentioned wheel for displacing said carrier. 105 110 115 120

20. In apparatus of the character described, in combination, a carrier for supporting thereon work of round section, a regulating wheel positioned on one side of said carrier and adapted to control the rotation of the work on said carrier, a grinding wheel operatively related to said carrier and movable in the general direction of said carrier, a power-driven reciprocating member, and means connecting said member to said grinding wheel, 125 130

said means including a lost-motion connection, and means for varying the length of the stroke of movement of said grinding wheel.

21. In apparatus of the character described, in combination, a carrier for supporting thereon work of round section, a grinding wheel related to said carrier and rotatable at a relatively high speed, a regulating wheel rotatable at a relatively low speed related to said carrier and having an operative surface exposed for action on said work which is of greater extent longitudinally of said carrier than the operative surface of said grinding wheel, said regulating wheel being rotated to present an operative surface traveling in a direction relative to the operative surface of said grinding wheel to control the rotation of the work, and means for giving said grinding wheel a linear movement longitudinally of said carrier and relative to the operative surface of said regulating wheel.

22. In apparatus of the character described, in combination, a carrier for supporting thereon work of round section, a grinding wheel positioned on one side of said carrier and rotatable at a relatively high speed, a regulating wheel positioned on the other side of said carrier and rotatable at a relatively low speed, said wheels being adapted to present adjacent operative surfaces traveling in opposite directions and one of said wheels having an operative surface which is peripheral, whereby the operative surface of one wheel gradually approaches the operative surface of the other, and means for automatically displacing said carrier between said approaching operative surfaces to move the work into or out of operative relation to the operative surfaces of said wheels.

23. In apparatus of the character described, in combination, a carrier for supporting thereon work of round section, a grinding wheel positioned on one side of said carrier and rotatable at a relatively high speed, a regulating wheel positioned on the other side of said carrier and rotatable at a relatively low speed, said wheels being adapted to present adjacent operative surfaces traveling in opposite directions and said regulating wheel having an operative surface which is peripheral, whereby the operative surface of said regulating wheel gradually approaches the operative surface of said grinding wheel, and automatic means for displacing said carrier between said approaching operative surfaces to move the work into or out of operative relation to the operative surfaces of said wheels.

24. In apparatus of the character described, in combination, a grinding wheel adapted to be rotated at a relatively high speed, a regulating wheel adapted to be rotated at a relatively low speed, said wheels being adapted to present approaching operative surfaces traveling in opposite directions, a carrier ex-

tending between said wheels and adapted to support work of round section thereon for free lateral movement with respect thereto, and automatic means for displacing said carrier in a direction to carry said work into or out of operative relation to said approaching surfaces of said two wheels.

25. In apparatus of the character described, in combination, a grinding wheel adapted to be rotated at a relatively high speed, a regulating wheel adapted to be rotated at a relatively low speed, said wheels being adapted to present approaching operative surfaces traveling in opposite directions, a carrier extending between said wheels for supporting thereon work of round section, and automatic means effective to bring about a movement of the work in a direction parallel to itself and into or out of operative relation with respect to said approaching operative surfaces of said two wheels.

26. In apparatus of the character described, in combination, a pair of abrasive wheels adapted to present adjacent operative surfaces in approaching relation, a carrier between said wheels for supporting work for action thereon by said wheels and mounted to be movable to change the relation of the work to said approaching operative surfaces, and automatic means for displacing said carrier.

27. In apparatus of the character described, in combination, a pair of abrasive wheels adapted to present adjacent operative surfaces in approaching relation, a carrier between said wheels for supporting work for action thereon by said wheels and mounted to be movable to change the relation of the work to said approaching operative surfaces, means for displacing said carrier to move the work thereon between more distant portions of the operative surfaces of said wheels, and automatic means effective upon the displacement of said carrier for discharging the work therefrom.

28. In apparatus of the character described, in combination, a pair of abrasive wheels adapted to present adjacent operative surfaces in approaching relation, a carrier between said wheels for supporting work for action thereon by said wheels and mounted to be movable to change the relation of the work to said approaching operative surfaces, means for displacing said carrier to move the work thereon between more distant portions of the operative surfaces of said wheels, and automatic means effective after a predetermined movement of said carrier to discharge the work from said carrier.

29. In apparatus of the character described, in combination, a pair of abrasive wheels adapted to present adjacent operative surfaces in approaching relation, a carrier between said wheels for supporting work for

- action thereon by said wheels and mounted to be movable to change the relation of the work to said approaching operative surfaces, means for moving said carrier to carry the work thereon between more distant portions of the operative surfaces of said two wheels and adapted to permit a return movement of said carrier, a plunger associated with said carrier adapted upon movement thereof to discharge the work from said carrier, and means effective to retract said plunger prior to the completion of said return movement of said carrier to permit the positioning on said carrier of another work piece. 70
15. 30. In apparatus of the character described, in combination, a pair of abrasive wheels adapted to present adjacent operative surfaces in approaching relation, a carrier between said wheels for supporting work for action thereon by said wheels and mounted to be movable to change the relation of the work to said approaching operative surfaces, means for moving one of said wheels lengthwise of said carrier during its action upon the work, automatic means for displacing said carrier to carry the work between more distant portions of the operative surfaces of said two wheels, and means adapted to permit discharge of the work from said carrier when thus displaced. 80
25. 31. In apparatus of the character described, in combination, a pair of abrasive wheels adapted to present adjacent operative surfaces in approaching relation, a carrier between said wheels for supporting work for action thereon by said wheels and mounted to be movable to change the relation of the work to said approaching operative surfaces, means for moving one of said wheels lengthwise of said carrier during its action upon the work, automatic means for displacing said carrier to carry the work between more distant portions of the operative surfaces of said two wheels, and automatic means acting in timed relation with respect to said carrier displacing means for ejecting the work from said carrier upon the latter being thus displaced. 90
30. 32. In apparatus of the character described, in combination, a pair of abrasive wheels adapted to present adjacent operative surfaces in approaching relation, a carrier between said wheels for supporting work for action thereon by said wheels and mounted to be movable to change the relation of the work to said approaching operative surfaces, means for displacing said carrier to carry the work between more distant portions of the operative surfaces of said wheels, means adapted to be automatically operated upon the displacement of said carrier for ejecting the work therefrom, and means for predetermining at will the extent of the time interval between the operation of said last two mentioned means. 100
33. In apparatus of the character described, in combination, a grinding wheel adapted to be rotated at a relatively high speed, a regulating wheel adapted to be rotated at a relatively low speed, said wheels being adapted to present approaching operative surfaces traveling in opposite directions, means extending between said wheels for holding work of round section in operative relation to said wheels and arranged to be displaced in a direction to change the relation of the work thereon with respect to said approaching operative surfaces, and means driven from said regulating wheel for displacing said work-holding means. 110
34. In apparatus of the character described, in combination, a grinding throat adapted for simultaneous grinding and rotating action upon work of round section and comprising three means, one of which is in the form of a grinding wheel adapted to be rotated at a relatively high speed, another of said means being in the form of a regulating wheel adapted to be rotated at a relatively low speed and in a direction to present an operative surface traveling in a direction relative to that of the operative grinding wheel surface to control the rotation of the work, and the third of which means includes a member for holding work of round section in operative relation to said two wheels; means for moving one of said means toward or away from one of the remaining means, means for causing movement of the work in a general direction lengthwise of the grinding throat, and means for giving said grinding wheel a moving stroke in the general direction of the grinding throat. 120
35. In apparatus of the character described, in combination, a grinding throat adapted for simultaneous grinding and rotating action upon work of round section and comprising three means, one of which means is in the form of a grinding wheel adapted to be rotated at a relatively high speed, another of said means being in the form of a regulating wheel adapted to be rotated at a relatively low speed and in a direction to present an operative surface traveling in a direction relative to that of the operative grinding wheel surface to control the rotation of the work, and the third of which means includes a member for holding work of round section in operative relation to said two wheels; mechanism adapted upon operation thereof to change the relation of one of said means with respect to the other; and means acting in timed relation with respect to said mechanism for causing movement of the work in a general direction lengthwise of said member. 130
36. In apparatus of the character described, in combination, a grinding throat adapted for simultaneous grinding and rotating action upon work of round section and

comprising three means, one of which means is in the form of a grinding wheel adapted to be rotated at a relatively high speed, another of said means being in the form of a regulating wheel adapted to be rotated at a relatively low speed and in a direction to present an operative surface traveling in a direction relative to that of the operative grinding wheel surface to control the rotation 5 of the work, and the third of which means includes a member for holding work of round section in operative relation to said two wheels; power driven means adapted in recurring sequence to move one of said means 10 relative to the remaining means; and means acting in timed relation with respect to said power driven means for causing movement of the work lengthwise of said member.

37. In grinding apparatus, in combination, 20 a grinding throat in which work of round section is received for simultaneous grinding and rotation, said grinding throat including a grinding wheel rotatable at relatively high speed, a regulating wheel rotatable at relatively low speed, said wheels being adapted to present adjacent operative surfaces traveling in opposite directions, said wheels being opposed to one another and having their operative surfaces substantially approaching each 25 other so as to form a grinding throat of varying width, and a member for holding work in operative relation to said two wheels, and means for moving said work-holding member in a direction to carry the work toward the narrower portion of said grinding throat, 30 thereby to effect progressive reduction in diameter of the work, means for ejecting a work piece from said grinding throat; and means for operating said last two mentioned 35 means in sequence.

38. In grinding apparatus, in combination, a grinding throat in which work of round section is received for simultaneous grinding and rotation, said grinding throat 45 including a grinding wheel rotatable at relatively high speed, a regulating wheel rotatable at relatively low speed, said wheels being adapted to present adjacent operative surfaces traveling in opposite directions, said 50 wheels being opposed to one another and having their operative surfaces substantially approaching each other so as to form a grinding throat of varying width, and a member for holding work in operative relation to said two wheels, and power-controlled means 55 for moving said work-holding member in a direction to carry the work toward the narrower portion of said grinding throat, thereby to effect progressive reduction in diameter 60 of the work, and means for limiting the movement of said work-holding member.

39. In grinding apparatus, in combination, a grinding throat in which work of round section is received for simultaneous grinding and rotation, said grinding throat including 65

a grinding wheel rotatable at relatively high speed, a regulating wheel rotatable at relatively low speed, said wheels being adapted to present adjacent operative surfaces traveling in opposite directions and having their operative surfaces substantially approaching so as to form a grinding throat of varying width, means for moving a work piece substantially transversely of its axis into said grinding throat, means for moving a work piece out of said grinding throat, and operating means for actuating said work moving means and connected to one of said means through a lost motion connection. 70

40. In grinding apparatus, in combination, a grinding throat in which work of round section is received for simultaneous grinding and rotation, said grinding throat including a grinding wheel rotatable at relatively high speed, a regulating wheel rotatable at relatively low speed, said wheels being adapted to present adjacent operative surfaces traveling in opposite directions and having their operative surfaces substantially approaching so as to form a grinding throat of varying width, means for moving a work piece relative to said grinding throat and in a direction substantially transverse to the axis of the work piece, means for moving a work piece relative to said grinding throat and in a direction substantially axially of the work piece, and means adapted upon operation to actuate said work moving means but connected to one of said work moving means through a lost motion connection. 75

41. In grinding apparatus, in combination, a grinding throat in which work of round section is received for simultaneous grinding and rotation, said grinding throat including a grinding wheel rotatable at relatively high speed, a regulating wheel rotatable at relatively low speed, said wheels being adapted to present adjacent operative surfaces traveling in opposite directions and having their operative surfaces substantially approaching so as to form a grinding throat of varying width, means for moving a work piece relative to said grinding throat and in a direction substantially transverse to the axis of the work piece, means for moving a work piece relative to said grinding throat and in a direction substantially axially of the work piece, a spring for controlling the movement of one of said work moving means, means for actuating one of said work moving means, and means including a lost motion connection between said actuating means and said spring for controlling the action of said spring. 100

42. In grinding apparatus, in combination, a grinding throat in which work of round section is received for simultaneous grinding and rotation, said grinding throat including a grinding wheel rotatable at relatively high speed, a regulating wheel rotatable at relatively low speed, said wheels being adapted 105

to present adjacent operative surfaces traveling in opposite directions and having their operative surfaces substantially approaching so as to form a grinding throat of varying width, means for moving a work piece relative to said grinding throat and in a direction substantially transverse to the axis of the work piece, means for moving a work piece relative to said grinding throat and in a direction substantially axially of the work piece, means for actuating one of said means throughout its effective range of movement, and means operative upon the completion of a predetermined portion of said range of movement for actuating the other of said work moving means.

43. In grinding apparatus, in combination, a grinding throat in which work of round section is received for simultaneous grinding and rotation, said grinding throat including a grinding wheel rotatable at relatively high speed, a regulating wheel rotatable at relatively low speed, said wheels being adapted to present adjacent operative surfaces traveling in opposite directions and having their operative surfaces substantially approaching so as to form a grinding throat of varying width, means for moving a work piece relative to said grinding throat and in a direction substantially transverse to the axis of the work piece, means for moving a work piece relative to said grinding throat and in a direction substantially axially of the work piece, means for actuating both of said work moving means, and means operative upon the completion of a predetermined portion of the range of movement of one of said work moving means for halting the movement of the other.

44. In grinding apparatus, in combination, a grinding throat in which work of round section is received for simultaneous grinding and rotation, said grinding throat including a grinding wheel rotatable at relatively high speed, a regulating wheel rotatable at relatively low speed, said wheels being adapted to present adjacent operative surfaces traveling in opposite directions and having their operative surfaces substantially approaching so as to form a grinding throat of varying width, a movable work positioning member adapted upon movement to move a work piece into or out of said grinding throat in a direction substantially transverse to the axis of the work piece, a plunger movable along said grinding throat and in a direction substantially axially of the work piece, means for actuating said positioning member, and means for actuating said plunger so that the latter commences its operative stroke at a time intermediate of the beginning and completion of a movement of said positioning member.

45. In grinding apparatus, in combination, a grinding throat in which work of round section is received for simultaneous grinding and rotation, said grinding throat including

a grinding wheel rotatable at relatively high speed, a regulating wheel rotatable at relatively low speed, said wheels being adapted to present adjacent operative surfaces traveling in opposite directions and having their operative surfaces substantially approaching so as to form a grinding throat of varying width, a movable work positioning member adapted upon movement to move a work piece into or out of said grinding throat in a direction substantially transverse to the axis of the work piece, a plunger movable along said grinding throat and in a direction substantially axially of the work piece, means for actuating said positioning member first in a direction to move a work piece into said grinding throat and then in a direction to permit movement of a work piece out of said grinding throat, and means operating during a first portion of said first-mentioned movement of said work positioning member for moving said plunger in one direction and for moving said plunger in reverse direction during a later portion of said second-mentioned movement of said positioning member.

46. In grinding apparatus, in combination, a grinding throat in which work of round section is received for simultaneous grinding and rotation, said grinding throat including a grinding wheel rotatable at relatively high speed, a regulating wheel rotatable at relatively low speed, said wheels being adapted to present adjacent operative surfaces traveling in opposite directions and having their operative surfaces substantially approaching so as to form a grinding throat of varying width, a movable work positioning member adapted upon movement to move a work piece into or out of said grinding throat in a direction substantially transverse to the axis of the work piece, a plunger movable along said grinding throat and in a direction substantially axially of the work piece, means for actuating said positioning member first in a direction to move a work piece into said grinding throat and then in a direction to permit movement of a work piece out of said grinding throat, means adapted upon being operated to move said plunger axially into or out of said grinding throat, and mechanism for operating said last-mentioned means from said actuating means, said mechanism being constructed to prevent entry of said plunger into the grinding throat during a portion of the movement of said positioning member in one direction and a portion of the movement thereof in its other direction.

47. In grinding apparatus, in combination, a grinding wheel adapted to be rotated at a relatively high speed, a regulating wheel, means including a shaft rotated at relatively low speed for driving said regulating wheel to give the latter a low surface speed, thereby to control the rotation of work of round section interposed between said two wheels, said

wheels being adapted to present approaching surfaces traveling in opposite directions, means for holding work of round section in operative relation to said wheels and arranged to be displaced in a direction to change the relation of the work thereon with respect to said approaching operative surfaces, means driven from said slow speed shaft for displacing said work-holding means, and means also operated from said slow speed shaft and in timed relation to said displacing means for causing movement of work relative to said work-holding means.

48. In grinding apparatus, in combination, a grinding wheel adapted to be rotated at a relatively high speed, a regulating wheel, means including a shaft rotated at relatively low speed for driving said regulating wheel to give the latter a low surface speed, thereby to control the rotation of work of round section interposed between said two wheels, said wheels being adapted to present approaching surfaces traveling in opposite directions, a carrier between said wheels for supporting thereon work of round section and mounted to be movable to change the relation of the work to said approaching operative surfaces, means operated from said slow speed shaft for moving said carrier to carry the work thereon between more distant portions of the operative surfaces of said two wheels and to give said carrier a return movement, and means responsive to movement of said carrier for causing discharge of work therefrom when in a position between more distant portions of said two wheels.

49. In grinding apparatus, in combination, a grinding wheel adapted to be rotated at a relatively high speed, a regulating wheel, means including a shaft rotated at relatively low speed for driving said regulating wheel to give the latter a low surface speed, thereby to control the rotation of work of round section interposed between said two wheels, said wheels being adapted to present approaching surfaces traveling in opposite directions, a carrier between said wheels for supporting thereon work of round section and mounted to be movable to change the relation of the work to said approaching operative surfaces, means operated from said slow speed shaft for moving said carrier to carry the work thereon between more distant portions of the operative surfaces of said two wheels and to give said carrier a return movement, and means also driven from said slow speed shaft for effecting movement of a work piece relative to said carrier when the latter has been moved to a position between more distant portions of said two wheels.

50. In grinding apparatus, in combination, a grinding wheel adapted to be rotated at a relatively high speed, a regulating wheel adapted to be rotated at a relatively low

speed, said wheels being adapted to present approaching operative surfaces traveling in opposite directions, a carrier between said wheels for supporting thereon work of round section and mounted to be movable to change the relation of the work to said approaching operative surfaces, cam means for effecting movement of said carrier, work-moving mechanism adapted upon actuation to effect movement of a work piece relative to said carrier, and means responsive to actuation of said cam means for actuating said work-moving mechanism.

51. In grinding apparatus, in combination, a grinding wheel adapted to be rotated at a relatively high speed, a regulating wheel, means including a shaft rotated at relatively low speed for driving said regulating wheel to give the latter a low surface speed, thereby to control the rotation of work of round section interposed between said two wheels, said wheels being adapted to present approaching surfaces traveling in opposite directions, a carrier between said wheels for supporting thereon work of round section and mounted to be movable to change the relation of the work to said approaching operative surfaces, reciprocable means having connections with said carrier to effect recurring movements thereof, mechanism driven from said slow speed regulating wheel for reciprocating said means, and means operating in timed relation with the movement of said carrier for effecting movement of a work piece relative to said carrier.

52. In grinding apparatus, in combination, a grinding throat adapted for simultaneous grinding and rotating action upon work of round section and comprising three means, one of which means is in the form of a grinding wheel adapted to be rotated at a relatively high speed, another of said means being in the form of a regulating wheel adapted to be rotated at a relatively low speed and in a direction to control the rotation of work during grinding action thereon by said grinding wheel, and the third of which means includes a member for holding work of round section in operative relation to said two wheels; and means driven from said slow speed regulating wheel for moving one of said means.

53. In grinding apparatus, in combination, a grinding throat adapted for simultaneous grinding and rotating action upon work of round section and comprising three means, one of which means is in the form of a grinding wheel adapted to be rotated at a relatively high speed, another of said means being in the form of a regulating wheel adapted to be rotated at a relatively low speed and in a direction to control the rotation of work during grinding action thereon by said grinding wheel, and the third of which means includes a member for holding

work of round section in operative relation to said two wheels; and means driven from said slow speed regulating wheel for causing movement of a work piece relative to said grinding throat.

5 54. In apparatus of the character described, in combination, a carrier adapted to support thereon work of round section, a grinding wheel rotatable at relatively high speed and positioned on one side of said carrier, a regulating wheel on the other side of said carrier, means including a shaft rotated at relatively low speed for driving said regulating wheel to give the latter a slow surface speed, thereby to control the rotation of the work on said carrier, said wheels being adapted to present adjacent operative surfaces traveling in opposite directions, and means driven from said slow speed shaft for 10 giving said grinding wheel a reciprocating movement in the general direction in which said carrier extends.

15 In testimony whereof, I have signed my name to this specification this first day of 20 October, 1923.
